DOOR JAMB

Harry Grimes, Evergreen Park, Ill.

Application November 23, 1932, Serial No. 644,069

19 Claims. (Cl. 72—98)

This invention relates to a door jamb of sheet metal which is adapted to take the place of wooden jambs in buildings of all types, but being more particularly for office buildings constructed 5 of fire-proof materials.

One of the objects is to provide a door-jamb which comprises opposing frames adapted to be clamped in an opening of a wall.

Another object is to provide frames having 10 opposed protruding portions extending inwardly in the opening, having their marginal edges arranged in spaced relation, and strips adapted to connect these edges.

Another object is to provide novel clamping 15 means for clamping the frames together and to the wall. Another object is to provide a clamping unit which may be installed upon a finished wall, thereby eliminating any waste of time consumed in the cleaning and retouching thereof.

With these and other objects in view, the invention will be better understood by reference to the following specification and accompanying drawing, wherein like characters represent corresponding parts, and in which

Fig. 1 is an elevational view showing an opening in a wall with the casing attached thereto.

Fig. 2 is an enlarged transverse sectional view taken on the line 2—2 of Fig. 1.

Fig. 3 is a detail section taken on the line 3—3 of Fig. 2.

Fig. 4 is a perspective view of one of the supporting hooks.

Fig. 5 is a perspective view of one of the frames with parts broken away and shown in section.

Fig. 6 is a fragmentary perspective view of one of the connecting strips.

Fig. 7 is a perspective view of one of the brackets and

Fig. 8 is a detail section of a modified form of 40 connection for the prolonged portions.

In the drawing 1 represents a wall comprising a central tile portion 2 and plaster faces 3, and is provided with a U shaped opening 4. The plaster faces 3 terminate at the opening 4 in alignment 45 with outer face 5 of the tile 2. The wall 6 of the tile 2 is provided with openings 7 at intervals along the sides and top of the opening 4. Arranged in the openings 7 are the upper bight portions 8 of S shaped hooks 9 with the inner legs 10 thereof in abutment with the inner face 11 of the wall 6. A casing 12 comprising opposing frames 13 and 14 is arranged in the opening 4. The frames 13 and 14 are U shaped in elevation and in cross section, and are provided with prolonged portions 15, having their marginal edges

of S shaped formation at right angles thereto as shown at 16. The portions 16 are provided with aligned openings 17 at intervals, the openings in the wall 18 of the frame 14 being tapped and the openings in the wall 19 of the frame 13 60 being countersunk. The walls 20 of the portions 16 are spaced from the walls 18 to provide a channel 21. Arranged in the frames 13 and 14 are U shaped brackets 22 as clearly shown in Fig. 2. The brackets 22 are attached to the inner 65 faces of the frames as by welding and are arranged at intervals as shown in Fig. 1, and in aligned opposed relation. The brackets 22 are U shaped in plan, the legs 23 thereof being prolonged and are provided with offset end portions 70 24 having slots 25 formed therein. The portion 24 of the brackets 22 arranged in the frame 14 is offset slightly more than that of its opposing bracket. The frames 13 and 14 are adapted to be arranged in the opening 4 with the marginal 75 edges 26' of the portion 26 in abutment with the outer faces 27 of the wall 1, and the portions 15 extending inwardly in the opening 4 with the portions 16 in spaced relation. The offset portions 24 are adapted to extend beyond the portions 16. 80 The legs 28 and 29 are provided with slots 30, adapted to receive bolts 31. The portions 24 are adapted to be slipped over the bolts 31 and arranged in overlapping relation between the legs 28 and 29. With this arrangement accommoda- 85 tion is provided for walls of varying thickness.

U shaped strips 32 having their legs 34 arranged in the channels 21 are provided with openings 17', adapted to align with the openings 17, and the outer face of the bight portion 36 being 90 in alignment with the outer edge of bight portion 37 of the portions 16. Flat head screws 38 are adapted to screw into the tapped openings in wall 18 with the heads thereof arranged in the countersunk openings of the wall 19 and the ends 95 thereof in abutment with the inner face of the wall 39 of the portion 16. The strips 32 may be made of varying sizes to accommodate walls of varying thickness. The portions 16 and strips 32 serve to provide a door-stop, the arrangement 100 being such that when a door mounted in closed position, one face of the door will be in abutment with the wall 19. From this it will be seen, that when the door is in closed position, all connecting means for the frames will be hidden. 105

If desired, the marginal edges of the portions 15 may be provided with a flange 16' bent at right angles thereto as shown in Fig. 8. The legs 34' and 35' of the strips 32' are provided with 110 tapped holes and countersunk holes, respectively

adapted to align with openings 17" in the flanges 16'. The strips 32' are adapted to straddle the flanges 16' and be connected thereto by flat-head screws 38'.

- 5 From the foregoing it will be seen that I have provided a door jamb which may be attached to a finished wall and which can be adjusted for walls of varying thickness. The frames may be painted and packed for shipment in compact form with 10 the walls 20 of one set of frames in abutment and the portions 15 of another set of frames in abutment with the portions 26.

It is to be understood that various changes may be made in the details of construction without departing from the spirit of the invention or 15 the appended claims.

Having thus described my invention, what I claim is:

1. A metal casing, comprising opposing casings adapted to embrace the edge of a wall having 20 an opening therein, opposed brackets carried by said casings, and means carried by the faces of said opening adapted to clamp said brackets together.

2. A metal casing, comprising opposing casings adapted to embrace the edge of a wall, opposed brackets carried by said casings having slotted end portions, and means carried by said wall adapted to clamp said end portions together.

3. A metal casing, comprising opposing casings adapted to embrace the edge of a wall, said casings being U shaped in cross section opposed brackets carried by said casings having slotted end portions arranged in overlapping relation, and means carried by said wall adapted to clamp said brackets together.

4. A metal casing, comprising opposing casings adapted to be attached to opposite sides of a wall having an opening therein, said casings being prolonged inward and having their marginal edges in spaced relation, means for connecting said edges, opposed brackets carried by said casings having offset slotted ends arranged in overlapping relation, and means carried by the faces of said opening for clamping said brackets together.

5. A metal casing comprising opposed casings adapted to be attached to opposite sides of a wall having an opening therein, said casings being prolonged inwardly and having their marginal edges in spaced relation, means for connecting said edges together, S shaped brackets carried by the faces of said opening, opposed brackets carried by said casings having slotted offset ends adapted to be arranged in said S shaped brackets, and means for clamping said ends to said S shaped brackets.

6. A metal casing comprising opposed casings adapted to be attached to opposite sides of a wall having an opening, said casings being prolonged inward and having spaced ends, flanges formed on said ends, U shaped strips adapted to embrace said ends, means for locking said strips to said ends, opposed brackets carried by said casings and having slotted offset ends arranged in overlapping relation, and brackets carried by the faces of said opening and means for clamping said offset ends to said last named brackets.

7. A metal casing comprising opposed casings adapted to be attached to a wall having an opening, means for securing said casings to opposite sides of the wall, said casings being prolonged inward and having perforated spaced S shaped margins, U shaped strips adapted to be arranged in said margins and having perforations adapt-

ed to align with the perforations in said margins, and screws adapted to be arranged in said openings to lock said strips and margins together.

8. A metal casing comprising opposed casings, adapted to be attached to a wall having an opening therein, said casings being prolonged inward and having spaced margins, said margins having channels formed at right angles thereto, connecting strips having parallel legs adapted to be mounted in said channels, said channels and legs having aligned openings therein, and screws adapted to be arranged in said openings whereby to lock said channels and legs together, and means for attaching said casings to opposite faces of said wall.

9. In combination, in a device of the class described, including a wall having an opening therein, a metal casing comprising opposed frames, brackets carried by said frames, said brackets being arranged in opposed relation at 95 intervals and having slotted offset ends overlapping, S shaped brackets carried by said wall, means for clamping said overlapping ends to said S shaped brackets, said frames being prolonged inward and having their margins spaced, said 100 margins having S shaped portions bent at right angles there, U shaped strips adapted to embrace the inner lips of said S shaped portions, said S shaped portions and strips having aligned openings arranged at intervals, and screws adapted 105 to be inserted in said openings.

10. In combination, in a device of the class described, including a tile wall having an opening therein, the faces of said opening being perforated, hook members having one end connected 110 to said wall in said perforations, a sheet metal casing comprising opposed frames, brackets carried by said frames arranged in opposed relation, said brackets having offset slotted end portions arranged in overlapping relation in the other 115 ends of said hooks, said other ends being perforated, bolts extending through said perforated ends and said slotted ends, said frames being prolonged inwardly, and U shaped strips adapted to connect the marginal edges of said prolonged 120 portions.

11. A metal casing comprising opposed casings adapted to be attached to opposite sides of a wall having an opening, said casings being prolonged 125 inward and having spaced ends, flanges formed on said ends, U shaped strips adapted to embrace said ends, means for locking said strips to said ends, opposed brackets carried by said casings, and means carried by the faces of said opening adapted to clamp said brackets together.

12. A metal casing comprising opposed casings adapted to be attached to a wall having an opening, means for securing said casings to opposite sides of the wall, said casings being prolonged inward and having spaced margins, channels formed 135 at said margins, U shaped strips adapted to be arranged in said channels, said channels and strips having aligned openings, and screws adapted to be arranged in said openings whereby to lock said channels and strips together.

13. In combination, in a device of the class described, including a wall having an opening therein, said opening having perforations in the faces thereof, hook members adapted to be mounted in said perforations, a casing comprising opposed 145 casings, brackets carried by said casings in opposed relation, and means for clamping said brackets to said hook members.

14. In combination, in a device of the class described, including a wall having an opening 150

therein, said opening having perforations in the faces thereof, hook members adapted to be mounted in said perforations, a casing comprising opposed casings, said casings being prolonged inwardly and having their marginal edges in spaced relation, means for connecting said edges, opposed brackets carried by said casings, and means for clamping said brackets to said hook members.

15. A metal casing comprising opposing casings adapted to embrace the edge of a wall having an opening therein, opposed brackets carried by said casings, and means carried by the faces of said opening adapted to clamp said brackets together in spaced relation to said faces.

16. A metal casing comprising opposed casings adapted to embrace the edge of a wall, opposed brackets carried by said casings and having offset slotted ends, hook members carried by said wall, and means for clamping said slotted ends to said hook members.

17. A metal casing comprising opposed casings adapted to embrace the edge of a wall, opposed brackets carried by said casings and having offset slotted ends, supporting brackets carried by said wall and having U shaped outer portions, said

offset ends adapted to be arranged in said U shaped portions in overlapping relation, and bolts adapted to be arranged in said slotted ends and U shaped portions whereby to clamp said opposing brackets to said supporting brackets.

18. A metal casing comprising opposed casings adapted to be attached to a wall having an opening, means for securing said casings to opposite sides of the wall, said casings being prolonged inward and having spaced margins, said margins having their ends bent at right angles to said inwardly projecting portions and having aligned perforations, connecting strips adapted to straddle said ends and having perforations adapted to align with the perforations in said ends, and screws adapted to be arranged in said aligned perforations.

19. A metal casing comprising opposed casings adapted to embrace the edge of a wall having an opening therein, said casings being U shaped, opposed brackets carried by said casings, and means carried by the faces of the said opening adapted to clamp said brackets together.
